CLAIM

The ornamental design for a rosary, as shown and described.

DESCRIPTION

FIG. 1 is a front perspective view of a rosary showing my new design;

FIG. 2 is a rear perspective view thereof;

FIG. 3 is an enlarged left side elevational view of the medal portion thereof;

FIG. 4 is an enlarged left side elevational view of the crucifix portion thereof;

FIG. 5 is an enlarged fragmentary left side elevational view of the double heart element thereof; and

FIG. 6 is an enlarged fragmentary right side elevational view of the double heart element thereof.

Portions of the rosary visible in FIGS. 3 and 4 have been omitted for ease of illustration.
